SELF-CLOSING GATE

Lon R. Smart and Mart Nelson,
Rocksprings, Tex.

Application December 29, 1937, Serial No. 182,309

4 Claims. (Cl. 39—84)

This invention relates to gates for use on highways, private roads, walks, exits, etc., an object being to provide a simple, compact and efficient structure which will open freely when pressed against and, after being released, will close automatically, the closing operation being effected without the use of springs or supplemental weights.

A further object is to provide a gate the working parts of which are fully protected from snow, ice, and dirt so that the gate will operate readily under all conditions.

A still further object is to provide a gate which can be made either single or double.

Another object is to provide a gate which can be easily set up for use.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

In the accompanying drawing the preferred form of the invention has been shown.

In said drawing

Figure 1 is a view partly in elevation and partly in section of the gate, parts being broken away.

Figure 2 is a plan view.

Referring to the figures by characters of reference 1 designates a base plate having an opening 2 above which is formed an upwardly extending sleeve 3 while opposed ears 4 extend downwardly from the plate at opposite sides of the opening. These ears are adapted to receive set screws 5 or the like which serve to engage the lower end portion of a spindle 6 seated snugly in the sleeve 3 and extending upwardly therefrom, the upper end of the spindle being preferably screw-threaded as shown at 7 and engaged by nuts 8 constituting an adjustable stop.

Sleeve 3 is formed on its outer surface with a spiral rib 9 engaged by a tubular block or nut 10 the inner surface of which has a groove 11 pitched similarly to the rib 9 and in which said rib is seated. This tubular nut or block 10 is seated snugly within the lower end of a housing member 12 in the form of an elongated tube, said tube being fastened to the nut or block 10 by screws 13 or the like.

The tubular housing 12 is of sufficient length to completely house the spindle 6 and its upper end is closed preferably by a screw cap 14. With-

in the upper portion of the tubular housing 12 is a centering block 15 held in place by screws 16 and this block has a central opening 17 within which spindle 6 is adapted to slide.

Ears 18 are carried by the housing 12 near the top and bottom thereof. These ears are arranged in pairs and where a double gate is provided, two oppositely extending pairs are located adjacent the bottom of the gate and two additional pairs are oppositely extended from the top portion of the housing. This latter construction has been shown in the drawing.

Mounted between the ears of the upper and lower pairs are the upper and lower corner portions respectively of gate frames 19 of any preferred construction and each of which preferably includes a diagonally disposed reinforcing rod 20 having tensioning means such as a turnbuckle 21. The two frames 19 are extended in opposite directions, in a double gate, and each of them has projecting fingers 22 adapted to bear laterally against a stop post P as shown particularly in Figure 2, thereby to limit rotation of the gate when gravitating along the spiral rib 9.

When the gate is to be set up for use the plate 1 is supported on a base B of concrete or the like in which are anchored attaching bolts A. Thus the spindle 6 and the tubular housing 12 will be supported in vertical position and as long as the cap 14 is in place the said spindle, block 10, and spiral rib 9 will be protected from dirt and moisture.

When the gate is closed the block 10 is in lower or normal position and the fingers 22 are pressed laterally against post P. When it is desired to open the gate it is merely necessary to thrust one of the frames 19 away from the post P engaged by its fingers 22. As the gate is thus swung, the block 10 which moves therewith, will ride upwardly on the spiral rib 9, thereby bodily raising the complete gate. After the gate has been released, the weight thereof will cause block 10 to gravitate along rib 9 and this action will, in turn, cause the gate to swing back to closed position.

Obviously the gate will operate in the same manner whether it be a single gate or a double gate. If it is a single gate, only one of the frames 19 would be used and there would only be one post P.

What is claimed is:

1. A gate of the class described including a base plate, a sleeve thereon having a spiral rib extending therearound, a spindle, a tubular hous-

- ing into which the spindle extends, means secured in the housing for support and engagement by the spiral rib, guiding means secured in the housing and sliding on the spindle, and a gate frame extending radially from the housing.
5. 2. A self-closing gate including an attaching plate, a sleeve extending upwardly therefrom, a spiral rib extending around the sleeve, a spindle, a tubular housing in which the spindle extends, guiding means in the housing slidably engaging the spindle, an adjustable stop on the spindle for engagement by the guiding means when lifted thereagainst, a block supported and engaged by the spiral rib, and a gate frame extending radially from the housing, said frame constituting means, when thrust against, for feeding the block along the spiral rib to elevate the gate relative to the spindle.
10. 3. A self-closing gate including a spindle, means for anchoring the same at one end, said means including a sleeve and a spiral rib extending around the sleeve, a housing surrounding the spindle, a closure for the upper end of the housing, means secured in the lower portion of the housing for rotatably engaging the sleeve
15. 25

and rib to raise or lower said housing relative to the spindle, a spindle-engaging guide within and carried by the housing, an adjustable stop on the spindle and above the guide, and a gate frame extending radially from the housing and 5 constituting means for rotating said housing relative to the spindle.

4. A self-closing gate including a spindle, means for anchoring the same at one end, said means including a sleeve and a spiral rib extending around the sleeve, a housing surrounding the spindle, a closure for the upper end of the housing, means secured in the lower portion of the housing for rotatably engaging the sleeve and rib to raise or lower said housing relative to the 10 spindle, a spindle-engaging guide within and carried by the housing, an adjustable stop on the spindle and above the guide, and a gate frame extending radially from the housing and constituting means for rotating said housing relative to the 15 spindle, the pitch of the rib being such as to cause the gate to gravitate and rotate when released for movement in one direction.
